SUCTION CLEANING APPARATUS

Philip B. Ellis, Ridley Park, Pa., assignor to
Electrolux Corporation, Dover, Del., a corpora-
tion of Delaware

Application November 16, 1935, Serial No. 50,129
Renewed August 4, 1937

5 Claims. (Cl. 15—156)

My invention relates to suction cleaning apparatus and particularly to nozzle structures therefor of the type generally disclosed and claimed in my copending application, Serial No. 9,360, filed March 5, 1935, and it has for an object to provide improved apparatus of this kind.

A further object of my invention is to provide a form of nozzle which, when in use, is sealed about its perimeter to the surface to be cleaned and wherein the air for cleaning is circulated through the nozzle and impinged against the surface to be cleaned within the confines of the sealing boundary.

A still further object of my invention is to simultaneously brush the article being cleaned and to bathe the surface thereof with air at high velocity.

These and other objects are effected by my invention as will be apparent from the following description and claims taken in connection with the accompanying drawings, forming a part of this application, in which:

Fig. 1 is a view of my improved nozzle structure applied to a suction cleaner of conventional design;

Fig. 2 is a plan view of my improved nozzle; Fig. 3 is a sectional view taken along the line III—III of Fig. 2;

Fig. 4 is a bottom view of the nozzle showing its contact face;

Fig. 5 is a section taken along the line V—V of Fig. 4; and,

Fig. 6 is a sectional view taken along the line VI—VI of Fig. 3.

Referring now, particularly, to Fig. 1, my improved nozzle, generally indicated at 10, is shown applied to a conventional portable suction cleaner which may include a blower unit 11, a flexible conduit 12 and a rigid conduit or handle 13. The apparatus operates in a well known manner in that, air, laden with the dirt removed from the article being cleaned, such as, for example, a carpet, is drawn through the nozzle 10, handle 13 and conduit 12 by the blower unit 11, in which separation of the dirt from the air is effected before the air is returned to the ambient atmosphere. The nozzle is reciprocated over the carpet by the operator by means of the handle 13.

In order that the nozzle 10 may be maintained in engagement with the carpet over its entire surface, regardless of the elevation of the hand of the operator or the angularity of the handle 13, a pivotal connection, best shown in Fig. 6 and indicated generally at 14, is provided. The pivotal connection 14 permits the handle 13 to

be lowered from the position shown in Figs. 1 and 6 without disturbing the engagement of the nozzle 10 with the carpet, so that the nozzle may be admitted beneath furniture or other objects where low head room is encountered.

Reference will now be had to Figs. 2 to 6, inclusive, wherein my improved nozzle is shown in detail. It includes a relatively flat body portion 15, having edge portions 16 and 17 which are, alternately, leading and trailing edges as the nozzle is reciprocated across the carpet. The sides of the body portion 15 are preferably rounded or ovalled as shown at 18. A relatively flat surface 21 is provided on the bottom of the body 15 for contact with the carpet or article 16 being cleaned. The body portion 15 further includes an elongated channel 22 adjacent the center thereof and formed in the contact face 21. The ends of the channel 22 are spaced inwardly from the ovalled sides 18.

As best shown in Figs. 3 and 6, the pivotal connection 14 includes a swivel member 23 having trunnions 24 journaled in the body portion 15. The member 23 has a main air passage 25 formed therein which communicates, at its inner end, 25 with a transversely-extending air passage 26 extending through the trunnions 24; the passage 26 communicating at both ends with the channel 22. The passage 26 communicates further with the channel 22 by means of a relatively wide port 30 27 which extends for a major portion of the length of the trunnions 24.

The trunnions 24 are rotatably mounted in a bearing seat 28 formed in the body portion 15, which seat is cut away or slotted, as shown at 29, 35 to provide communication between the port 27 and the channel 22. The slot 29 may be coextensive with the length of the port 27, as shown in Fig. 3, with the end portions 31 of the trunnions 24 bearing in the seat 28 throughout their 40 entire periphery or diameter. It will be understood that the trunnions 24 are fitted to the seat 28, alignment of the trunnions 24 and seat 28 being insured by the continuous end portions 31 of the trunnions 24 which bear in the seat 28 45 throughout their circumference. Movement of the trunnions 24 axially of the seat 28 is prevented by inwardly projecting flanges 32 at the terminal portions of the seat 28.

A cap 33 is attached to the body portion 15, 50 preferably, by means of screws 34 and includes a seat 35 which complements the seat 28 to define the bearing for the trunnions 24. The cap 33 is slotted as shown at 36 in Figs. 2, 3, and 6 to permit the member 23 to be moved down-

wardly when the nozzle is moved beneath an object offering low head room.

The various passages formed in the contact face 21 of the nozzle will now be described. In 5 addition to the channel 22, the face 21 has a plurality of recesses 37, spaced outwardly from both sides of the channel. These recesses 37 communicate with the channel 22 by means of respective ducts 38. As shown, the end recesses 10 are each provided with a single duct, the intermediate recesses with a plurality of ducts, while the central recesses are each provided with a central duct and two divergent ducts. It will be 15 particularly noted that the recesses 37 are all spaced inwardly from the perimeter of the nozzle so as to form a continuous sealing face 40.

Air from the ambient atmosphere is conducted to the recesses 37 by means of respective openings 39, which may be axially disposed with respect to the recesses 37. Preferably, the inner ends of the 20 openings 39 project into the recesses 37 as shown particularly in Fig. 6 so that air entering the openings is directed at high velocity into engagement with the carpet.

In order that material, such as, for example, 25 threads or hair, may be disengaged from the nap of a carpet, I provide brushes 42 and 43, preferably located on each side of the chamber 22. As shown, these brushes 42 and 43 are detachably 30 secured to the body portion 15 by means of screws 44 and 45, respectively. The brushes 42 and 43 are preferably disposed adjacent the central portion of the channel 22 and are of substantial length.

In the operation of the nozzle, the contact face 35 21 bears against the carpet by its own weight and by the additional weight of the handle 13. When the blower unit 11 is motivated, the nozzle bears against the carpet with additional force due to 40 the air seal effected by that portion of the contact face which lies outwardly of the recesses 37 and the ends of channel 22 and the consequent difference in pressure between the suction pressure prevailing in the recesses 37, ducts 38, and 45 channel 22 and the atmospheric pressure prevailing upon the upper surface of the nozzle.

As the nozzle is reciprocated across the carpet, air is drawn from the ambient atmosphere through the openings 39 and is impinged at high 50 velocity against the carpet. Imbedded dust or relatively heavy dirt or grit is thereby dislodged and entrained in the stream of air. The air is deflected by the carpet and flows radially from beneath the center of the openings 39 into the 55 recesses 37, in which it moves circumferentially and then enters the ducts 38 to be delivered into the channel 22.

The various air streams from the duct 38 flow to the center of the channel and pass into the 60 passage 26 through the end portions thereof and through the slot 29 and port 31 as indicated by the arrows in Fig. 3. The air, laden with dirt, then passes into the discharge passage 25 and is conveyed therefrom to the blower duct 11. Fibrous material is dislodged by the brushes 42 65 and 43 and carried away by the air stream.

It will be apparent that communication between the port 27 and slot 29 is maintained, regardless of the position of the handle 13 and 70 swivel member 23, as the port 31 is made of sufficient width to register with the slot 29 in all positions of the member 23.

From the foregoing, it will be apparent that I 75 have provided an improved suction cleaner nozzle structure which produces a new and novel clean-

ing action in that the outer boundary of the contact face of the nozzle is sealed to the carpet, making the entire stream of air effective to impinge against the carpet for dislodging the dirt.

While I have shown my invention in but one 5 form, it will be obvious to those skilled in the art that it is not so limited, but is susceptible of various changes and modifications without departing from the spirit thereof, and I desire, therefore, 10 that only such limitations shall be placed thereupon as are imposed by the prior art or as are specifically set forth in the appended claims.

What I claim is:

1. In suction cleaning apparatus, a body having 15 a flat bottom surface for engaging the surface to be cleaned, said bottom surface being elongated, an outlet slot located centrally of the bottom surface, extending in the direction of the major axis thereof and terminating short of the ends of said bottom surface, a multiplicity of air 20 nozzle openings spaced from each other and extending downwardly through the body, said openings being located between each side boundary of the bottom surface and the slot and on opposite sides of the transverse centerline of the 25 bottom surface, and separate passageways extending between the lower ends of the respective openings and the slot, said passageways extending from their respective openings in directions inclined with respect to the slot in the direction 30 of the transverse centerline of the bottom surface.

2. In suction cleaning apparatus, the combination 35 of a body having a bottom surface for engagement with a surface to be cleaned, outlet means including a slot located in an intermediate portion of the bottom surface, a plurality of openings extending downwardly through the body for impinging air against the surface to be cleaned, said openings being spaced from the slot, and brush means for engaging the surface to be 40 cleaned, said brush means being located between the slot and the openings.

3. In suction cleaning apparatus, the combination 45 of a body having an elongated bottom surface for engagement with a surface to be cleaned, an outlet slot extending longitudinally and substantially centrally of the bottom surface, a series 50 of spaced openings extending downwardly through the nozzle body in spaced relation with respect to the outlet slot and on each longitudinal side thereof, passageways provided in the bottom surface for affording communication between the openings and the slot, and brushes disposed adjacent to the slot on opposite sides thereof, said brushes being secured to the bottom surface 55 of the nozzle body and arranged to engage the surface to be cleaned.

4. In suction cleaning apparatus, the combination 60 of a nozzle body having an elongated bottom surface for engagement with a surface to be cleaned and having a seat portion located above the bottom surface and within the perimeter of the bottom surface; a swivel member having an upwardly extending air conduit portion and transversely projecting trunnion portions, said 65 trunnion portions fitting the seat portion of the nozzle body and said conduit portion projecting outwardly of the nozzle body, and a cap engaging the trunnion portions of the fitting for attaching the fitting to the nozzle body, said cap having an 70 opening encompassing the conduit portion of the fitting and arranged to afford angular movement thereof, and means for securing the cap to the nozzle body.

5. In suction cleaning apparatus, the combina- 75

tion of a nozzle body having an elongated bottom surface for engaging a surface to be cleaned and having an air outlet channel formed therein, said channel extending downwardly through the nozzle body, spaced seats provided in the nozzle body, a fitting having a conduit portion and a transversely extending trunnion portion, said trunnion portion bridging the seats and having openings provided in its ends and between the seats for

affording communication between the conduit portion of the fitting and the channel of the nozzle body, and a cap secured to the nozzle body for retaining the fitting in assembled relation with the nozzle body, said cap being so constructed and arranged as to afford limited angular movement of the fitting relative to the nozzle body. 5

PHILIP B. ELLIS.
